METHOD FOR ROASTING PENCIL LEADS

Richard Zückert, Bohmisch-Budweis, Czechoslovakia, assignor to the firm "Koh-i-noor" tuz-kárna L. & C. Hardtmuth, Čes., Budejovice, Czechoslovakia

Application June 8, 1937, Serial No. 147,061
In Germany July 17, 1936

1 Claim. (Cl. 263—52)

The roasting of pencil leads is carried out usually in such a manner that the leads are placed into rectangular graphite- or chamotte-containers and covered with coal dust or graphite powder, whereupon these containers are heated in chamber- or muffle-furnaces. A tunnel-furnace has also been employed herefor, through which the containers are pushed on small carriages or ceramic balls.

10 This known method possesses the inconvenience that, it is practically impossible to maintain a sufficiently uniform heat acting upon the individual leads, and further to ensure that the heat acts uniformly on the individual lead 15 from the one end to the other. This is due partly to the flame- or flue-gas being conducted around the containers, and partly to the difference in the heat supplied to the bottom plate and to the side walls of the containers, apart 20 from the additional heating of the lead ends by the end walls of the containers which are heated also. On the other hand the mechanical properties of the finished pencil leads depend to a considerable degree on the height and duration 25 of the temperature acting upon them, the breaking strength and the hardness of the lead increasing up to a certain temperature and burning period, but drop again if temperature and burning period are further increased.

30 To overcome this inconvenience the containers, in which the pencil-leads are located are of cylindrical shape and passed the one directly behind the other through a stationary heating tube, heated from the outer side or by means of heating 35 bodies accommodated in the wall of the tube, the diameter of this heating tube being only slightly larger than that of the containers so that it is still possible to convey the containers through the heating tube without grazing the wall thereof, 40 but nevertheless, larger air quantities are prevented from flowing through between the heating tube and the containers. Hereby a perfectly uniform heat acts upon the whole outer surface of the containers, the result of which is a uniform, 45 concentrical penetration of heat to the leads contained in the containers. Owing to the direct succession of the containers, the end faces of the same remain unheated, so that the cause for a more rapid heat absorption of the leads at the 50 ends than at the middle no longer exists.

An embodiment of the invention is illustrated, by way of example, in the accompanying drawings, in which—

Fig. 1 shows in vertical section a lead burning 55 furnace according to the invention.

Fig. 2 a cross-section on line A—B of Fig. 1 on larger scale.

Fig. 3 shows in larger scale part of Fig. 1 with the packing arrangement for the gap between heating tube and containers in cross-section. 5

Fig. 4 is a top plan view of Fig. 3.

Fig. 5 shows a single container with lid in perspective view.

As shown in Figs. 1 and 2, the leads 1 to be roasted are accommodated in vertical, cylindrical 10 containers 2 which descend through a stationary vertical heating tube 3 and therefore the leads lie parallel to the axis of the heating tube. Each container (see Fig. 5) consists of a hollow cylinder 2a, open at the upper end and closed by a 15 plane bottom at the lower end, and of a lid 2b placed on the top end of the container. This lid 2b consists of a plate with a low upwardly directed cylindrical rim, designed to carry the next higher container, and which has at two opposite 20 points recesses for a transverse rod designed to support the column of containers each time the lowermost container is discharged from the heating tube, as will be hereinafter described.

The heating tube 3 composed for instance of 25 three pieces is of such small internal diameter that between its inner wall and the containers only a comparatively narrow annular gap remains which just allows the column of containers to pass through the heating tube without any 30 danger of grazing, whereas the passage of air between the containers and the inner wall of the heating tube is made very difficult. Owing to this arrangement the heating tube is prevented from acting like a chimney and considerable 35 quantities of air cannot pass through the same, and unfavorably influence the efficiency of the heating as well as the regulation of the heating effect upon the leads.

The heating tube 3 is electrically heated by 40 means of heating coils 4 in the carriers 5. The space between the carriers 5 and the outer wall 8 of the furnace is filled with insulating mass 7; in the hottest portion of the furnace insulating bricks 6 are arranged between the carriers and 45 the insulating mass. The furnace is subdivided into five heat zones, of which the uppermost and the lowermost are not directly heated, whereas, the middle one is most strongly heated by closely wound coils, the number of coil windings in the 50 upper zone (pre-heating zone) and in the lower zone (cooling zone), particularly in the upper zone, being less great. In this manner the heat condition in every cross-sectional plane of the furnace can be regulated as desired.

The column of containers rests at the lower end upon a suitable supporting device 9, which may for instance consist of the rack of a crab-bar, which allows the column to slowly descend in known manner until the lowermost container can be removed, the next higher container and with the same the whole column of containers having been previously supported by a transverse rod (see Fig. 3). The supporting device can then ascend again, the head of the rack coming to bear during the last portion of its stroke against the lower surface of the, now lowermost container so that the carrying rod can be removed, whereupon the column of containers can descend again by the height of one container.

Figs. 3 and 4 show a part of Fig. 1 on larger scale and illustrate details of a packing device, designed to further prevent the chimney-like sucking up of air in the heating tube 3. Just above the carrying rod 10, which cooperates in the above explained manner with the support 9, three segment-like brushes 12 with bristles 13 radially pressed against the outer surface of the container which is at the same height, are arranged in a box 11 fixed on the carrying frame of the furnace, the descending container brushing along the bristles of these brushes. The brushes prevent practically any air from passing between the heating tube and the container column. The concentric position of the brush-segments 12 can be accurately regulated by means of set-screws 14 or, if desired, by means of concentrically acting pressure springs.

The supporting device becoming operative during the removal of the lowermost container from the container column is shown in detail in Figs. 3 and 4. The transverse rod 10 rests upon transverse beams 15 fixed on the carrying frame of the

furnace so that these beams can be adjusted by means of screws 16.

Details of the furnace shown may be modified without departing from the chief idea of the invention. The heating coils may, for instance, be placed in the body of the heating tube, or the axial graduation of the heating may be attained not by the differing number of the windings per axial length unit, but by altering the thickness of the wire of the heating coil, by special connection measures and the like. Instead of electrical heating, which will be preferably employed owing to the easy installation and regulability and the fact that their cost is not high as compared with their high heating efficiency, any other kind of heating may be selected; only such kinds of heating are excluded in which flue gases flow through the space between the inner wall of the heating tube and the container column. The containers may for instance be of prismatic instead of cylindrical shape and of any desired multi-cornered cross-section. Instead of one single packing arrangement for the space between the heating tube and the containers several arrangements, for instance two or three rows of brushes may be provided, one row above the other.

I claim:

A method for roasting pencil leads in closed cylindrical containers which are successively conducted through a heated vertical channel, consisting in arranging the pencil leads standing in the closed cylindrical containers parallel to the axis thereof, piling the filled containers one upon the other in vertical alignment to form a column of only slightly smaller diameter than and filling practically the entire cross sectional area of the heated channel, and then conducting the filled containers through the heated vertical channel.

RICHARD ZÜCKERT.
